(57) **CLAIM**
The ornamental design for a rear door trim panel for an automobile, as shown and described.

(***) Term: **14 Years**

DESCRIPTION

(21) Appl. No.: **29/476,509**

FIG. 1 is a front elevational view of a rear door trim panel for an automobile in accordance with our new design;

(22) Filed: **Dec. 13, 2013**

FIG. 2 is a top plan view of the rear door trim panel in accordance with our new design of FIG. 1;

(51) **LOC (10) Cl.** 12-16

FIG. 3 is a bottom plan view of the rear door trim panel in accordance with our new design of FIGS. 1 to 2;

(52) **U.S. Cl.**

FIG. 4 is a right side elevational view of the rear door trim panel in accordance with our new design of FIGS. 1 to 3;

(53) **USPC** **D12/195**

FIG. 5 is a left side elevational view of the rear door trim panel in accordance with our new design of FIGS. 1 to 4;

(58) **Field of Classification Search**

FIG. 6 is a front-right side perspective view of the rear door trim panel in accordance with our new design of FIGS. 1 to 5; and,

USPC D12/195, 193, 414, 190, 196; 180/190;

280/750-752; 296/190.01-191, 70,

296/193.08, 145, 153, 37.1-37.13, 149,

296/146.1; D15/17, 28; D10/46, 98,

D10/102-103; 49/501-502; D8/302-303

FIG. 7 is a front-left side perspective view of the rear door trim panel in accordance with our new design of FIGS. 1 to 6. The rear view of the rear door trim panel forms no part of the claimed design.

Our new design includes the mirror image of the rear door trim panel shown in FIGS. 1 to 7.

The shading of gray in the drawings is provided for purpose of depicting the shape of the three-dimensional article.
